ATTORNEY.

UNITED STATES PATENT OFFICE.

SPENCER C. CARY, OF BROOKLYN, NEW YORK, ASSIGNOR TO CARY MANUFACTURING COMPANY, OF NEW YORK, N. Y., A CORPORATION OF NEW YORK.

WIRE TIE FOR BUNDLES OF VARIOUS KINDS.

Application filed August 21, 1924. Serial No. 733,275.

This invention is a wire tie for bundles such as shooks, paper, shipping packages, and the like, wherein a tie wire under tension is precluded from cutting into the corners of the package, so as to result in injury to the components of the bundle, and at the same time is held securely upon said bundle, whereby said tie wire serves as an efficient binder for holding the bundles intact and for adding stability thereto.

The invention embodies a tie wire and a plurality of metallic corner members which in the service of the tie wire are positioned at the several corners of the package, said metallic members performing the primary function of affording bearings for the tie wire to resist the tendency of said wire, under the effect of the tension applied thereto, to become embedded in the material of the package, particularly at the corners thereof.

Each of the embedding-resistance members is a metallic plate provided with a keeper, or a plurality of keepers, through which the tie wire is threaded with the object of ably connecting the resistance-members to the tie wire, thus permitting the tie wire to be easily inserted within the keepers and permitting the resistance member to be slipped along the tie wire so as to occupy the required relation to the bundle or package around the corner of which the resistance member is bent to occupy a snug relation thereto. Said embedding-resistance member is economically manufactured by stamping the same in the form of a flat plate from a piece of sheet metal, and cutting and offsetting the metal of the plate to produce the desired number of keepers, the latter being integral with the plate and positioned in an offset relation thereto and in alinement with each other.

It is desirable to thread the tie wire easily and quickly through the keepers of the member. The operation of slitting and offsetting the keepers from the metal of the plate has a tendency to raise the edges of the metal adjacent the cut and offset portions which produce the keepers, such raised edges of the metal being in the path of the tie wire so as to hinder, to an appreciable extent the free passage of said tie wire. In my invention such obstruction to the free passage of the tie wire is obviated by depressing the edges of the metal in an opposite direction to the offsetting of the keepers, the effect of

which is to produce lips extending in one direction from the plane of the plate, whereas the keepers extend in an opposite direction from said plate, whereby the tie wire is adapted to be inserted with great ease and freedom through said keepers of the member.

Other functions and advantages will appear from the following description taken in connection with the drawings, wherein—

Figures 1, 2 and 3 are perspective views of my wire tie in connection with different kinds of bundles.

Figure 4 is a detail plan view of the embedding-resistance plate constituting a part of the bundle tie.

Figure 5 is a longitudinal section on the line 5—5 of Figure 4.

A is the tie wire and B are the members threaded on said wire and bendable at the corners of the bundle to preclude the tie wire from sinking into the material of said bundle under the tension which is applied to said wire.

It should be stated that it is now common practice to apply a tie wire around a package by placing tension on said wire and locking the ends of the wire together so as to retain said wire under the required tension, it being usual to employ wire tying machines of well known kinds for such purposes.

The application of wire ties under tension to certain kinds of packages results in injury to the components of the package, such as asphalt shingles, shooks, paper, and, in fact, to shipping boxes composed of paper cartons or thin wooden veneer boxes. In short, a wire tie is almost universally used by putting the same under tension around various kinds of bundles or packages, because the tie to be efficient must be under tension in order to add stability and strength to the bundle and to retain itself in position; but shippers of certain commodities or users of thin light packing boxes complain that the wire is injurious to the components of the package and to the shipping boxes because the wire tends to injure such bundle components and the boxes when the tie is applied so tightly as to become embedded in the materials. To preclude such embedding of the tie wire, I provide the wire bearing plates B, and to secure co-operation between the wire and the plates, the latter are constructed

as shown in Figures 4 and 5 with keepers C, two or more of which are provided on each plate. The plate is stamped in a single piece from sheet metal to the required dimensions and form, and at this stamping operation the plate is cut transversely on parallel lines as at c (see Figure 5), and the metal between such parallel cuts c is displaced to one side of the plane of the plate, i. e. is offset laterally in a manner to produce the keepers C.

The operation of cutting the plate and offsetting the keepers has a tendency in the ordinary cutting dies to raise a burr or fin at the lines of the cuts, which burr or fin 15 protrudes to a certain extent from that face of the plate on which the keepers are formed and which burr or fin is adjacent the keeper so as to lie in the path of the tie wire when the latter is threaded through the keepers, 20 thus interfering to a marked extent with the passage of the tie wire. In my invention this defect is overcome by depressing the metal to produce the lips D which are formed at the cut edges of the plate adjacent 25 the keepers, as shown clearly in Figure 5. The lips protrude from the plate in an opposite direction to the offsetting of the keepers, and such lips are inclined with respect to the plane of the plate, whereby the lips 30 perform the function of directing the tie wire toward the plane of the top face of the plate should the end of such wire have a tendency to strike against the cut edge when threading the tie wire in the keepers. The 35 plate is composed of sheet metal of such character that is bendable easily in the hands of the workman, it being preferable to bend the plate transversely intermediate its ends, as indicated by the score line E of Figure 5, 40 such line of bend being between the keepers C.

My invention is useful for binding many different kinds of bundles or packages, and as indicating the mode of use I have shown 45 three examples in Figures 1, 2 and 3. A bundle of asphalt shingles is shown in Figure 1 as having two of the ties applied thereto; a bundle of paper or other flat material is shown as having two ties in Figure 2; 50 whereas in Figure 3 there is shown a carton, box or other container composed of light material, such as paper board, thin veneer, or light thin boards. In each instance the ties are applied by passing the

wires around the bundle, bending the plates 55 B at the corners of said bundle, placing tension on the tie wires, and fastening the meeting ends of the tie wire. The wires are applied tightly for the double purpose of compressing the bundle to a certain extent 60 so as to add to the strength and stability of the bundle and to adapt the ties for holding themselves in place on the bundle and thus prevent said ties from becoming displaced whether by shrinkage of the components or 65 material of the bundle or by rough handling in transportation. The metal plates are between the bundle and the wire ties and extend around the corners of the bundle to afford bearing surfaces for the wires, whereby 70 the plates are held frictionally on the bundle and they act efficiently in precluding the wire ties from sinking or embedding in the material of the bundle.

Although I have shown and described the 75 invention as adapted more particularly for round wire ties, it is apparent that a thin narrow band may be used by threading it through keepers of appropriate size on metal plates, and that the ends of the narrow 80 bands may be joined or sealed by appropriate means.

My invention obviates the use of boards on the top and the bottom of bundles for preventing the wires or bands from sinking 85 into the material. The metal plates are cheaper and easier to handle than the top and bottom boards, and they afford protection to the corners of the bundle, it being well known that top and bottom boards are 90 liable to slip out of place when tying the bundle and do not adequately protect the corners of the package.

Having thus fully described the invention, what I claim as new and desire to secure 95 by Letters Patent is:

In a device of the class described, a bearing member for a tie composed of a single piece of metal provided on one face with tie receiving keepers and on the other face with tie directing lips, said keepers and lips being co-operable in facilitating the threading of the bearing member upon a tie so as to slide freely thereon.

In testimony whereof I have hereto signed 105 my name this 16th day of August, 1924.

SPENCER C. CARY.
